(57) **CLAIM**

The ornamental design of an air curtain cooler, as shown and described.

DESCRIPTION

FIG. 1 is a front, top and right side perspective view of an air curtain cooler showing my new design;

FIG. 2 is a front, top and left side perspective view thereof;

FIG. 3 is a back, top and left side perspective view thereof;

FIG. 4 is a front elevation view thereof;

FIG. 5 is a back elevation view thereof;

FIG. 6 is a right side elevation view thereof;

FIG. 7 is a left side elevation view thereof; and,

FIG. 8 is a top plan view thereof.

The motor and fan elements shown in the drawing views in broken lines represent unclaimed subject matter and form no part of the claimed design.
